UNITED STATES PATENT OFFICE

FRANK B. DUNN, OF CONNEAUT, OHIO.

BRICK-CUTTING MACHINE.

1,122,704.

Specification of Letters Patent. Patented Dec. 29, 1914.

Application filed November 9, 1911. Serial No. 659,361.

To all whom it may concern:

Be it known that I, FRANK B. DUNN, a citizen of the United States, residing at Conneaut, in the county of Ashtabula and State of Ohio, have invented certain new and useful Improvements in Brick-Cutting Machines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to brick-cutting machines, and has for its object the provision in such machines of improvements in the platen, and in the guide-plate mechanism operating on the top of the clay column during the cutting operation; and improvements in the mechanism for supporting and operating said guide-plate mechanism, whereby I am enabled to construct a practically operative brick-cutting machine 20 which entirely overcomes the difficulties incident to brick-cutting machines as heretofore constructed.

25 Other features and advantages of my invention will appear hereinafter in the specification and claims.

I attain these objects and advantages by means of the construction, combination, and arrangement of mechanism hereinafter set forth and described, and illustrated in the 30 accompanying drawings in which:

Figure 1, shows a side view in elevation of a part of a brick-cutting machine embodying my invention. Fig. 2 is a top or plan view of the same. Fig. 3, is an end view in elevation of the same looking in the direction of the arrow in Figs. 1 and 2. Fig. 4, is a transverse section of the same on the line $x-x$ in Figs. 1 and 2 looking in the direction of the arrow in Figs. 1 and 2. Fig. 5, is a top or plan view of the guide-plate operating upon the clay-column during the cutting operation, and its supporting frame. Fig. 6, is a top or plan view of the platen, and that part of the machine frame upon which it is supported. Fig. 7, is an edge-wise view of the guide-plate and its supporting frame, looking in the direction of the arrow in Figs. 5 and 9. Fig. 8, is a side view in elevation of the same with the 40 guide-plate turned up. Fig. 9, is an end view of the same in elevation with the guide-plate turned up.

45 In these drawings I show my improvements applied to a brick-cutting machine provided with an oscillating cutter, the entire machine traveling in unison with a moving column of clay extending therethrough during the cutting operation, in which machine the supporting tracks A, the machine frame composed substantially of the end frames, B and side frame B', wheels b, supporting said machine frame upon the tracks A, the tripping and clutch mechanism C C' C², the driving gear D D', the shaft d of the gear D and the shaft d' of the gear D' mounted on the brackets B³ on the side-frames B' are all of the usual construction and arrangement, and detailed description thereof is deemed unnecessary.

50 The end-frames, B, are provided with downwardly extending brackets B² in which there is pivoted the supporting arms E of the cutter-yoke E' and these two cutter-yokes, one at each end of the machine, are provided with connecting-bars, e below the platen hereinafter described and e' above said platen, between which bars tensioned cutter-wires e² are secured in the usual manner. The platen is constructed preferably of a platen frame F provided with transverse slots f for the passage of the cutter-wires e². The platen frame F rests upon and is supported by the lugs b' on the inside faces of the end frames B of the machine. Upon the top of this platen frame F, I preferably secure plates f' which form the wearing surface of the top of the platen; and to the sides of the platen frame F I secure side-guides F' which have slots coinciding with the slots f in the platen frame. 55 These guides F' operate to retain the clay-column in place as it passes over the platen and during the operation of the cutting-wires thereon. The guides F' are preferably secured upon the top of the platen frame by means of bolts f'', so that they can be removed from the platen frame F when desired. The platen-frame and the guides secured thereto rest upon the lugs b', on the inside of the end-frames B and can be at any time removed from the machine and replaced by another platen for cutting brick of a different size, simply by removing the cutter-wires e². This platen and guide structure and its relation to the machine-frame 60 65 70 75 80 85 90 95 100 105 110

are clearly illustrated in the transverse section shown in Fig. 4, and in the plan view shown in Fig. 6.

For operating the cutter-yokes E' , I pivot 5 to each of said yokes somewhat below the platen F a pitman G which connects with a crank-disk D^2 mounted on the shaft d' . The gear and tripping mechanism being so arranged and adjusted that each semi-revolution 10 of the crank-disk D^2 will move the yokes E' so as to carry the tensioned cutting wires through the slots f in the platen F , so that each movement of the cutter-yokes will cut the clay-column upon the 15 platen into brick.

Upon the tops of the end frames B , I secure upright guides H H , and upon these guides H , I place an upwardly and downwardly movable part I , provided with vertical sleeves I' , fitting over the guides H and are freely movable up and down thereon. The preferred shape and configuration 20 of the parts I , being clearly shown in Figs. 5, 7, 8 and 9.

25 To the outer faces of the parts I , there is preferably pivoted upwardly extending arms J each being provided with a roller J' , mounted on a stud j , on the upper end thereof and extending over the peripheries 30 of the yokes E' . Upon the upwardly extending arms J , there are laterally extending arms J^2 , the outer end of which is pivoted to brackets B^4 on each end frame B , and on each of the yokes E' , there are two 35 preferably adjustable, wedge-shaped, parts E^2 , and E^3 , secured thereto at such points that they will pass under the rollers J' , at the completion of each traverse of the yokes E' , and operate through the upright arms 40 J , to raise the parts I , upward and retain them in such raised position until the yokes E' , start back on their return traverse. On the guides H above the sleeves I' , are placed spiral springs h secured by adjusting nuts 45 h' , which springs operate on the parts I , to force them downward to their normal positions.

Between the parts I , there is secured a 50 guide-plate L by means of removable pivots i , extending through the parts I and into the ends L' near the edge L^2 , the opposite edge L^3 resting upon the lugs i^2 , on the inside faces of the parts I , as illustrated in Figs. 4 and 7, and are secured in place by 55 means of removable bolts i' passing through the parts I , and into the ends L' , of the guide-plate L , as is clearly shown in Figs. 2 and 5, so that in operation the guide-plate L , is raised and lowered in unison with the 60 parts I , as shown in Fig. 3. The bolts i' , can be removed when desired and the guide-plate L , can then be turned up on the pivots i , out of the way, as illustrated in Figs. 8 and 9, and by broken lines in Fig. 3, and 65 when necessary to change the guide-plate to

make a brick of different size the removable studs i , and the bolts i' , can be removed, and the guide-plate L , removed from the machine and another guide-plate substituted therefor.

70 The guide-plate L , is preferably cast in the shape of a comb, the part L^2 , constituting the back thereof and the parts L^3 , the teeth with slots l , between them as illustrated in Figs. 2, 5 and 8, which slots l , coincide with the slots f in the platen frame F , and the slots f^3 , in the side-guides F' , when the guide-plate L , is in place on the machine.

75 To the under face of the teeth or bars L^3 , 80 I secure guide-plates M of the same width as the platen plates f' , and of sufficient length to enter between the guides F' , as illustrated in Figs. 3 and 4, so that when the parts I , and the guide-plate L , carried 85 thereby, more downward to their lowermost position a column of clay upon the platen will be firmly clamped between the platen-plates f' , and the guide-plates M . It is manifest that the under faces of the guide- 90 plates M may be made plain, or of any desired configuration, in which latter case the configuration on the guide-plates M will be impressed upon the upper edges of the bricks as they are being cut.

95 In operation a column of clay passes into the cutter upon the platen-plates f' between the side-guides F' , in the usual manner, and at predetermined times the machine travels 100 forward in unison with the column of clay and as it starts this movement the mechanism which actuates the cutter-yokes starts 105 and operates to rotate the crank-disks D^2 one half of a revolution, and when it starts to move the cutter-yokes they carry the 110 wedge-shaped parts E^2 , and E^3 , as the case may be, from under the rollers J' , on the arms J , connected with the parts I , and permit the parts I , and the guide-plate L , carried thereby to move downward, aided 115 by the action of the springs h , so as to firmly clamp a column of clay on the platen-plates f , down thereon during the passage of the cutter-wires therethrough, and as the cutter-yokes E' continue their movement, the 120 cutter-wires e^2 , enter the slots between the platen plates f and the slots between the plates M , and are carried transversely through the clay-column without any strain upon the driving mechanism of the machine 125 during said cutting operation, other than that incident to forcing the cutter-wires through the clay, and when the cutter-wires have passed out of the clay-column the wedge-shaped parts, E^2 , or E^3 , as the case 130 may be, immediately pass under the rollers J' , and operate to raise the parts I , and the guide-plate L , so as to release the cut-bricks, as is clearly shown in Figs. 3 and 4, and allow the bricks to be moved off of the 135

platen-plates f' , by the incoming column of clay; this operation being repeated at each movement of the cutter-yokes E' .

Having thus described my invention so as 5 to enable others to construct and utilize the same, I do not desire to limit myself to the exact form of mechanism shown and described, as many modifications therein may be made by those skilled in the art, without 10 departing from the spirit of my invention.

Therefore what I claim as new and desire to secure by Letters-Patent is;

1. The combination in a brick-cutting machine, of a frame, a slotted platen, for receiving and sustaining a column of clay, mounted on said frame, a vertically movable slotted guide-plate mounted above said platen and adapted to clamp a clay column thereon, yokes at the ends of the machine 15 frame, cutting-wire mechanism mounted on and carried by said yokes, mechanism for intermittently operating said yokes to carry the cutting-wires through a clay-column clamped upon the platen by said guide-plate, mechanism at the ends of said guide-plate communicating with said yokes, raised surfaces on said yokes adapted to engage the mechanism communicating with the 20 guide-plate as the movement of the yokes terminates and raise the guide plate off of the clay-column, substantially as set forth.
2. The combination in a brick-cutting machine of a frame, a slotted platen thereon, yokes carrying cutting wire mechanism 25 mounted near the ends of the machine frame, means for intermittently moving said yokes, vertical guides on the ends of the machine frame, parts movable up and

down on said guides, a slotted guide-plate so pivoted on and supported by said parts 40 that one edge thereof can be turned up when desired, vertical arms on said parts extending upward adjacent to the yokes, inclined surfaces so located on said yokes as to be engaged by said vertical arms to raise said 45 vertically movable parts and the guide-plate supported thereby as the movement of the yokes terminates, substantially as set forth.

3. The combination in a brick-cutting 50 machine of a frame, a slotted platen resting in supports on the ends of said frame so as to be readily removable therefrom, yokes carrying cutting-wire mechanism mounted on the ends of the frame, mechanism for intermittently moving said yokes, vertically 55 movable parts mounted on the ends of the machine frame adjacent to the yokes, arms extending upward therefrom adjacent to said yokes, rollers on the upper ends thereof, 60 a guide-plate so secured to and supported by said parts that it can be readily removed therefrom, and inclined surfaces adjustably secured to said yokes and so located thereon as to be engaged by the rollers on said arms 65 and raise said vertically movable parts and the guide-plate supported thereby as the movement of the yokes terminate in either direction, substantially as set forth.

In testimony whereof I affix my signature, in presence of two witnesses.

FRANK B. DUNN.
